DESIGN FOR A HANDBAG

Elizabeth Hawes, New York, N. Y.

Application March 3, 1936, Serial No. 61,457

Term of patent 3½ years

To all whom it may concern:

Be it known that I, Elizabeth Hawes, a citizen of the United States of America, residing in city of New York, county of New York, and State of New York, have invented a new, original, and ornamental Design for a Handbag, of which the following is a specification, reference being had to the accompanying drawing, forming part thereof,

Fig. 1 is a front view of a handbag showing my new design.

Fig. 2 is a rear view of a handbag as shown in Fig. 1.

Fig. 3 is a plan view view of a handbag as shown in Fig. 1.

I claim:

The ornamental design for a handbag, substantially as shown.

ELIZABETH HAWES.
